DESIGN FOR A UNIVERSAL AIRPLANE

Anton Fehrenbach, New York, N. Y.

Application May 1, 1933. Serial No. 47,942

Term of patent 3½ years

To all whom it may concern:

Be it known that I, ANTON FEHRENBACH, a citizen of the United States, residing at New York, in the county and State of New York, have invented a new, original, and ornamental Design for Universal Airplanes, of which the following is a specification, reference being had to the accompanying drawing forming a material part of this disclosure and in which:

Figure 1 is a top perspective view of an airplane, showing my new design.

Figure 2 is a side elevational view of my airplane.

Figure 3 is a bottom perspective view of the plane, showing the built-in pontoons.

I claim:

The ornamental design for a universal airplane as shown.

ANTON FEHRENBACH.
